UNITED STATES PATENT OFFICE.

JOHN HAYS HAMMOND, JR., OF GLOUCESTER, MASSACHUSETTS.

TORPEDO SUPPORTING AND LAUNCHING MECHANISM FOR AIRCRAFT.

1,403,159.

Specification of Letters Patent. Patented Jan. 10, 1922.

Application filed June 20, 1916, Serial No. 104,763. Renewed February 7, 1921. Serial No. 443,221.

To all whom it may concern:

Be it known that I, JOHN HAYS HAMMOND, Jr., a citizen of the United States, and a resident of Gloucester, county of Essex, 5 State of Massachusetts, have invented certain new and useful Improvements in Torpedo Supporting and Launching Mechanism for Aircraft, of which the following is a specification.

10 Some of the objects of this invention are to provide means responsive to radiant energy for detachably connecting a torpedo or other body to an air craft; to provide improved means for detachably connecting 15 a torpedo or other body to an air craft, in combination with means for initiating operation of the propelling means or other functioning means upon the torpedo or body; and to provide other improvements as will 20 appear hereinafter.

In the accompanying drawings, Fig. 1 is a side elevation of a hydro-aeroplane provided with torpedo supporting and launching mechanism constructed in accordance 25 with this invention; Fig. 2 a front elevation of the same; and Fig. 3 a diagrammatic view of one form of radio receiving means forming a part of this invention.

Referring to the drawings, one embodiment 30 of this invention is shown applied to a hydro-aeroplane 10, including a pair of floats 11 and 12 of any well known or suitable construction, above which is a flat plane 15 of any suitable construction, which is rigidly connected to the floats 11 and 12 respectively by means of a series of vertical posts or struts 16 and tie-rods 17.

For detachably connecting a torpedo 20 or other body to the hydro-aeroplane, so 40 that the torpedo will be suspended by the hydro-aeroplane above the water level when the hydro-aeroplane is supported by water, a rigid cylindrical bar 21 extends longitudinally of the hydro-aeroplane and the ends 45 of this bar 21 pass through and are rigidly secured in two pairs of spaced bearings 22, 22 and 23, 23 respectively, which are integral with or rigidly secured to the lower ends of oblique rigid rods or hangers 24, 24, 50 25, 25 respectively, the upper ends of which are rigidly secured to the under surface of the plane 15. The ends of the bar 21 are also rigidly secured in bearings 30 which are integral or rigid with cross bars 31 re- 55 spectively, which are each terminally secured to a corresponding pair of the vertical posts

16. The bar 21 is thus arranged centrally of the hydro-aeroplane and extends in such a direction that when the hydro-aeroplane is in the water the bar 21 will be substantially parallel to the surface of the water.

Between each pair of bearings 22, 22 and 23, 23, and rotatably mounted upon the bar 21, are a pair of rigid, separately rotatable jaws 35 and 36, which depend below the bar 21 and which have shanks 37 and 38 rigid therewith respectively, and which project upwardly from the bar 21. Each pair of jaws 35, 36 and their corresponding shanks 37 and 38 are arranged in a plane perpendicular to the bar 21 and to swing in that plane with respect to the bar 21. Each pair of jaws 35 and 36 is in the form of segments of a circle and is so arranged with respect to its shanks 37 and 38 that when 75 the jaws 35 and 36 are clamped tightly around the cylindrical torpedo 20 the upper ends of the shanks 37 and 38 will be brought together.

For normally clamping each pair of jaws 35, 36 tightly around the torpedo 20, and for simultaneously releasing both pairs of jaws to permit the torpedo to fall or be launched into the water, the upper ends of each pair of shanks 37, 38 are arranged to engage normally in a rigid inverted cup 40, which is rigidly secured to the lower end of an upwardly extending piston rod 41 which is arranged to reciprocate longitudinally through a bearing 42 rigidly secured to the 90 corresponding oblique rods 24, and to reciprocate through an opening provided therefor in the lower closed end 43 of a cylinder 44 which is rigidly secured at its upper end to the under surface of the plane 95 15 by means of bolts 45 which extend through a flange 46 provided upon the upper end of the cylinder. Each cup 40 is provided with ball bearings 47 arranged in a suitable internal raceway provided therefor in the cup and operative to engage against the upper ends of the corresponding shanks 37 and 38 to provide an anti-friction contact to permit of the easy withdrawal of the cup 40 from the shanks 37 and 38.

The upper end of each piston rod 41 is rigidly secured to a piston 50, which is arranged to reciprocate in the corresponding cylinder 44, and each piston 50 is normally pressed downwardly by means of a spiral 110 spring 51 which is compressed within each cylinder 44 above its piston 50.

For releasing the torpedo 20 from the hydro-aeroplane a pipe 55 communicates at its ends with the lower ends of the two cylinders 44 respectively, and communicates intermediate of its ends with a supply pipe 56 which is controlled by a valve 57 and which leads from a tank 58 or source of compressed air.

For releasing the torpedo 20 in response to radiant energy the valve 57 is arranged to be controlled by a solenoid 60 provided with a reciprocatory core 61 which forms a stem for controlling the valve 57 in a well known manner. One end of the solenoid 60 is connected by a conductor 62 to a brush 63 and the other end of the solenoid 60 is connected by a conductor 64 to one terminal of a battery 65, the other terminal of which is connected by a conductor 66 with a brush 67. The two brushes 63 and 67 are arranged to engage against a commutator 70 which is provided with a suitable contact or contacts 71 arranged to be engaged by the brushes 63 and 67 to close the circuit through the battery 65 and solenoid 60 when the commutator 70 is rotated into a proper position for that purpose. The commutator 70 is rigidly secured upon a shaft 75 extending longitudinally and axially therethrough and which is supported in suitable bearings (not shown) to rotate about an axis coincident with its longitudinal axis and fixed with respect to the plane 15.

For rotating the commutator 70 step by step in one direction, a ratchet 76 is rigidly secured to the shaft 75 and is arranged to be actuated by a pawl 77 which is pivotally secured to a gear 78 which loosely surrounds the shaft 75 and which is engaged by a rack 79 which is arranged to reciprocate in a fixed path with respect to the plane 15. For reciprocating the rack 79 one end of the rack is rigidly secured to a piston 80 which is arranged to reciprocate in a cylinder 81 fixed with respect to the plane 15 and having at one end an inlet and an outlet, both controlled by a valve having a valve stem 82, and the inlet being in communication through a pipe 82' with the supply pipe 56 leading from the tank 58 of compressed air. The valve stem 82 forms the core of a solenoid 83 which is in a circuit containing a battery 84 and a normally open switch 85 which is controlled by an electromagnet 86 arranged in the controlled circuit 87 of a gaseous audion 88 which is controlled by an oscillatory circuit 89 including a condenser 90 and an inductance 91. The inductance 91 forms the secondary of a transformer, the primary 92 of which is in series with an antenna 93 which is carried by the hydro-aeroplane 10. The parts for reciprocating the rack 79, including the radio receiving apparatus, with the exception of the main part of the antenna 93, are preferably arranged within a casing

94 which may be fixed upon the plane 15 or in any other suitable position upon the hydro-aeroplane.

For initiating the operation of the propellers 95 of the torpedo 20, as a result of and simultaneously with the releasing of the torpedo from the hydro-aeroplane, a lever 96 is pivotally secured to the torpedo and has one end projecting freely upwardly therefrom and which is arranged to be engaged and normally held in a fixed position by means of a corresponding hook 97 which is rigidly secured to one of the fixed bearings 23 or other suitable part of the hydro-aeroplane. The lever 96 is operatively connected in any suitable manner to the actuating mechanism of the propellers 95 and is so arranged that when the torpedo 20 is clamped securely in position between the two pairs of jaws 35 and 36 and the lever 96 is in engagement with the hook 97, the lever 96 will prevent the actuation of the propellers 95, but when the jaws 35 and 36 are opened and the free end of the lever 96 is therefore caused to rotate in an anti-clockwise direction as viewed in Fig. 1 with respect to the torpedo 20, the lever 96 will cause the initiation of the operation of the propellers 95.

For controlling the direction of movement of the hydro-aeroplane or the operation of the functioning devices carried by the hydro-aeroplane, the valve stem 61 may be connected to any suitable retarding means, such, for instance, as a dash pot 100 arranged so that the valve 57 will not open or operate to admit air from the tank 56 into the lower ends of the cylinders 44 unless the commutator 70 is permitted to remain in a suitable position for an appreciable and predetermined length of time, and the commutator 70 may be provided with other brushes 101 and 102 and corresponding segments 103 and 104 arranged in any suitable manner to control the direction of movement of the hydro-aeroplane or the operation of functioning devices carried thereby.

In the operation of the hereinbefore described supporting and launching mechanism, the two inverted cups 40 are pressed up either manually or by permitting compressed air to enter the lower ends of the two cylinders 44, and the two pairs of jaws 35 and 36 may then be clamped around the torpedo 20 after it has been lifted into a suitable position. By then permitting the two inverted cups 40 to engage over the upper ends of the corresponding shanks 37, 38, the torpedo 20 will be securely clamped in position by the two pairs of jaws 35, 36. When it is desired to release or launch the torpedo 20 and to initiate the operation of its propellers 95, a suitable number of signals or impulses of radiant energy are transmitted from any suitable sending station to the hydro-aeroplane to act upon the radio

receiving apparatus and to cause a suitable rotation of the commutator 70 into such a position as to close the circuit through the battery 65 and the solenoid 60, and to cause 5 the valve 57 to open to admit compressed air from the tank 58 through the pipe 56 and pipe 55 into the lower ends of the cylinders 44, thus causing the two pistons 50 to be pushed upwardly by the pressure of the air 10 and thus releasing the two pairs of jaws 35, 36 and permitting the torpedo 20 to fall, and simultaneously causing the lever 96 to be acted upon by the hook 97 to initiate the operation of the propellers 95 of the torpedo, 15 whereupon as soon as the torpedo strikes the water it will proceed immediately upon its course.

Although only a single form has been shown in which this invention may be embodied, it is to be understood that the invention is not limited to any specific construction, but might be applied in various forms without departing from the spirit of the invention or the scope of the appended claims.

Having thus fully described this invention, I claim:

1. The combination with a movable body, of means carried by said body including clamping members adapted to normally embrace an object to detachably connect the same to said body, and fluid actuated means including pistons having rods which engage said clamping members operative to permit the disengagement of said object from said 35 clamping members.

2. The combination with a movable body, of means carried by said body, including clamping members adapted to normally embrace an object to detachably connect the same to said body, pneumatic means including pistons having rods which engage said clamping members, and means responsive to radiant energy for actuating said pneumatic means.

3. The combination with a movable body, of pneumatic means including pistons having rods, means responsive to radiant energy for controlling said pneumatic means, pivotal clamping members for engaging an object to detachably connect the same to said body, said piston rods releasably engaging said clamping members to hold them against movement, and means actuated as a result of the release of said object from said body to initiate the functioning means carried by said object.

4. The combination with a body, of means including a pair of clamping members each

comprising a jaw and a shank for detachably connecting an object to said body, pneumatic means including a piston having a rod for engaging the shanks of said clamping members, and means responsive to radiant energy controllable of said pneumatic means to effect a release of said object from said body when rendered active.

5. On a hydro-aeroplane, in combination, means including a plurality of pairs of clamping members each comprising a jaw and a shank for detachably connecting an object to said hydro-aeroplane, pneumatic means including a plurality of pistons each having a rod which engages a pair of said shanks of said clamping members, and means responsive to radiant energy controllable of said pneumatic means as and for the purpose specified.

6. On a hydro-aeroplane, in combination, means including a plurality of pivotally mounted clamping members each comprising a segmental jaw and a shank for detachably connecting a torpedo to said hydro-aeroplane, pneumatic means, including a plurality of pistons each having a rod, cup-shaped elements at the free ends of said piston rods, anti-friction balls carried by said cup-shaped elements, said elements being adapted to engage a pair of said shanks in their normal positions, and means responsive to radiant energy controllable of said pneumatic means for disengaging the cup-shaped elements from said shanks, for the release of said torpedo.

7. The combination with a movable body, of means carried by said body including engaging members arranged to normally support an object to detachably connect said object to said body, and pressure operated means, including pistons connected to said engaging members, operative to detach said 100 engaging members from said object.

8. The combination with a movable body, of means carried by said body including engaging members arranged to normally support an object to detachably connect said object to said body, pressure operated means, including pistons connected to said engaging members, operative to detach said engaging members from said object, and means responsive to radiant energy for controlling 110 said pressure means to cause the release of said object from said body.

Signed at New York city, in the county 115 of New York and State of New York, this sixteenth day of June, A. D. 1916.

JOHN HAYS HAMMOND, JR.
